UNITED STATES PATENT OFFICE.

JAMES GILLESPIE, OF LINCOLN, ILLINOIS.

WASHING-MACHINE.

SPECIFICATION forming part of Letters Patent No. 313,318, dated March 3, 1885.

Application filed July 26, 1883. (No model.)

To all whom it may concern:

Be it known that I, JAMES GILLESPIE, a citizen of the United States, residing at Lincoln, in the county of Logan and State of Illinois, have invented certain new and useful Improvements in Washing-Machines, of which the following is a specification, to wit:

This invention relates to an improvement in washing-machines; and it consists in certain peculiarities of construction and arrangement, substantially as will be hereinafter more fully set forth.

In order to enable others skilled in the art to which my invention appertains to make and use the same, I will now proceed to describe its construction and operation, referring to the accompanying drawings, in which—

Figure 1 is an end elevation. Fig. 2 is a cross-section. Fig. 3 is a longitudinal section, 20 and Fig. 4 is a detail view of one of the boxes.

A represents a cylindrical box or casing, consisting of solid end pieces connected by stay-rods a and covered with zinc a' , and is formed with a hinged cover or lid, A', having suitable means for fastening it shut. This casing is mounted upon legs A^2 , as represented in Fig. 1, and is thus raised to a convenient height for operation. Each end of the cylindrical casing A is provided with a removable section, a^2 , sliding in vertical grooves in the end pieces and carrying the upper half of a two-part journal-box, b, the lower side of which is secured to the end of the casing. In these boxes b rest the journals b' of a slatted cylinder B, also having a hinged cover, B'. This cylinder is but little smaller than the interior of the outer casing, and the slats b^2 are beveled alternately upon the inner and outer sides, as represented in the section in Fig. 2. One of the journals b' extends entirely through the box b, and is provided on its outer end with a crank, B^2 , by which the slatted cylinder is revolved.

Within the cylinder B is a roller, C, formed with a corrugated surface, c, and supported by pins or journals C' in its ends resting in openings c' in the journals b' of the cylinder B. One of these pins C' passes entirely through the journal b' and the end of the outer casing, 50 and has its end squared for the attachment of a

crank, when desired. Ordinarily this roller is held stationary by a metal strap, c^2 , secured upon the outer end of the main casing, and engaging the squared end of the pin when the crank is removed. The journal-pins C' are 55 preferably formed with a screw-thread or a feather upon their points, so that when driven into the end of the roller they will be prevented from accidental displacement during the use of the machine.

In operation, the clothes to be washed are placed in the slatted cylinder and hot water poured into the outer casing. When the outer lid or cover is closed, the heat and steam are all confined within the machine, and as the 65 cylinder is revolved the steam and heated water are effectually forced through the clothes, cleansing them much more rapidly and thoroughly, as well as much easier, than by the ordinary mode of rubbing upon a board, and 70 does not wear or otherwise injure the garments. The alternate beveling of the slats upon the surface of the revolving cylinder not only enables this to be more easily operated, but serves to force the currents of water 75 through the cylinder and its contents. The inner fluted or corrugated roller may be revolved in an opposite direction to the cylinder by detaching the metal strap which holds it and replacing it with a crank, and the operation of the cylinder and roller in opposite 80 directions effects a cleansing of the garments much more rapidly.

Having thus fully described my invention, what I claim as new, and desire to secure by 85 Letters Patent, is—

In a washing-machine, the combination of an outer cylindrical case, an inner cylindrical cage having longitudinal slats alternately beveled in opposite directions, and a central 90 corrugated roller journaled in the journals of the cage and adapted to move independently thereof and to be locked, substantially as described.

In testimony whereof I affix my signature in 95 presence of two witnesses.

JAMES GILLESPIE.
